CARY PEEBELS, OF SANTA CLARA, CALIFORNIA.

Letters Patent No. 63,086, dated March 19, 1867.

IMPROVEMENT IN ADJUSTABLE HANDLES FOR FRUIT BOXES.

The Schedule referred to in these Letters Patent and making part of the same.

TO ALL WHOM IT MAY CONCERN:

Be it known that I, CARY PEEBELS, of Santa Clara, Santa Clara county, State of California, have invented a new and improved Adjustable Handle for Berry Boxes; and I do hereby declare the following description and accompanying drawings are sufficient to enable any person skilled in the art or science to which it most nearly appertains to make and use my said invention without further invention or experiment.

The nature of my invention is to provide an adjustable handle for strawberry boxes to be used in picking the fruit, so constructed as to clasp the box and hold it until filled, after which it can be easily detached and applied to another box. The necessity for such an invention will be found apparent from the fact that berries, especially strawberries, should be sent to market in the same boxes in which they are gathered, on account of the necessity of preserving the berries perfect, which cannot be done by rehandling and repacking.

In most cases strawberry boxes are round or square, with no convenient handle or arrangement for holding except by clasping by the thumb upon the top or edge of the box, with the fingers placed underneath, which soon becomes very tedious and wearisome for the hand, and in no case can more than one hand be employed at the same time; but, in case of necessity, when my invention is used, both hands can be occupied, by attaching the box to the body by means of a strap passing through the handle and fastened to the person engaged in picking.

To more fully explain my invention reference is had to the accompanying drawings and letters of reference marked thereon, in which—

Figure 1 is one form of my invention.

Figures 2 and 3 are modifications of the same.

A A, fig. 1, are two stout wires or pieces of iron, twisted together, as shown, for a portion of their length each way from the middle. The four projecting ends are then bent at right angles with the twisted portion, forming four arms, as shown at *b b* and *b' b'*. These arms *b b* are bent inward at their extremities, *c c*, forming four short prongs or dogs, which, having a less distance between them than the diameter of the boxes, can be firmly attached by separating the arms *b b* from *b' b'*, and then allowing them to spring back, thus forcing the points *c c* into the sides of the box, and holding it firmly. A strap may be attached, and the box supported by the body, thus allowing both hands to be used.

After filling a box the handle may be removed and applied to another box, as they are all of uniform size, the labor of gathering the fruit being thus rendered more expeditious and less fatiguing.

Having thus described my invention, what I claim, and desire to secure by Letters Patent, is—

A handle A, constructed with the arms *b b* and prongs *c c*, similar to that herein described, substantially as and for the purpose set forth.

In witness whereof I have hereunto set my hand and seal.

CARY PEEBELS. [L. s.]
